(57) **CLAIM**

The ornamental design a palm-size multi-functional massage device, as shown and described.

DESCRIPTION

FIG. 1 is a perspective view of a palm-size multi-functional massage device, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken from line 8—8' shown in FIG. 2; and,

FIG. 9 is also a perspective viewed from another angle thereof.
